UNITED STATES PATENT OFFICE

FRANKLIN R. WHITE AND JOHN J. WOOSTER, OF WATERBURY, CONNECTICUT, ASSIGNEES TO THE PATENT BUTTON COMPANY, OF WATERBURY, CONNECTICUT, A CORPORATION OF CONNECTICUT

FLEXIBLE BUTTON

Application filed November 3, 1930. Serial No. 493,136.

Our invention relates to new and useful improvements in buttons, and more particularly to what is known as the flexible type of button.

As is well known to those skilled in the art, it is often desirable to have a button wherein the head may move vertically and also tilt slightly or cant when lifted with the fingers, as this tilting or canting or vertical movement of the button head makes it easy to slip the same into the button hole.

One of the objects of the present invention, therefore, is to produce a flexible type of button that will be extremely cheap to manufacture and assemble and consisting of but two parts, each of the said parts being extremely simple in itself.

The present application is a companion to one filed of even date herewith and bearing Serial Number 493,135.

Still another object of the invention is to produce a flexible type of button wherein the button head may have a relatively thin upper surface and may be provided with an ornamental cap.

Still another object of the invention is to produce an eyelet which will loosely fit within the hub of the button head and which will allow the button head to move vertically with relation thereto and also allow the button head to slightly tilt or cant but, at the same time, will prevent the head from becoming detached from the eyelet.

Still another object of the invention is to produce an extremely cheap eyelet and which in its preferred form is provided with a closed top or dome so that when the prong of the tack fastener is driven up within the eyelet it will impinge against the upper inner surface of the dome of the eyelet, which is preferably of hard metal, and thus deform the prong of the tack and fill the enlarged dome-shaped top of the eyelet to thus rigidly secure the eyelet to the cloth.

With these and other objects in view, the invention consists in certain new and novel arrangements and combinations of parts, as will be hereinafter more fully described and pointed out in the claims.

Referring now to the drawings showing a

preferred form and a slightly modified form of eyelet,

Fig. 1 is a top plan view of the button head;

Fig. 2 is a sectional view thereof;

Fig. 3 is a sectional view of the button head with a cap placed thereon, a sectional view of the eyelet beneath the same and a bottom plan view of the eyelet;

Fig. 4 is a sectional view of the button head and showing the eyelet fitted and nested within the button head;

Fig. 5 is a view similar to Fig. 4 but showing the button head in its raised position;

Fig. 6 is a similar view but showing the tack fastener holding the button to the cloth, the dotted lines showing a tilting position of the button head;

Fig. 7 shows a slightly modified form of eyelet.

Referring now more particularly to the several views and Figs. 1 to 6 inclusive and for the moment to Figs. 1, 2 and 3, there is shown a button head 1, which is preferably formed of aluminum. These button heads are made from aluminum slugs or rods in the well known manner and can be cheaply made, as the aluminum is just subjected in a machine (not shown) to the action of dies.

It will be noticed that the button head 1 has the tapered rim 2 and is provided with a hollow hub 3, which is dome-shaped, as at 4. It will also be noticed that the body portion or upper part of the button head is relatively thin, as a metal cap 5 is to be secured thereon, which cap, of course, may have any desired insignia or trade-mark stamped therein. The relative thinness of the body of the button head may also be noticed, as compared with the button head shown in the companion application heretofore referred to.

It will further be understood that although this button head is stated as being made of aluminum, it will be understood that it also might be made of stainless steel or any other non-tarnishable metal alloy.

Referring now to the eyelet 6, which forms the base of the button and which forms a means for the button head to tilt on, reference is made to Figs. 3 to 6 inclusive. This

little eyelet 6 may be made of brass or may be made of tin or any other desired metal of sufficient hardness and comprises the cup-shaped base 7, the vertical walls of the hub 8, and the integral dome cover 9.

The diameter of the dome cover 9 is greater than the diameter of the hub of the eyelet or, in other words, the dome flares sharply outwardly, as at 10, and then is rounded or domed, as may be seen in the several views.

Now the diameter at 10 of the dome is such that it will slidingly fit within the walls of the hub 3 of the button head 1 and after this eyelet is placed in position, the lower edges of the walls 3 of the hub are crimped inwardly, as at 11, to slidingly fit about the vertical walls 8 of the eyelet but impinge against the flared portion 10 of the eyelet when the button head is raised with respect to the eyelet. In other words, the button head may move vertically on the hub of the eyelet but cannot become disengaged therefrom, as will be readily appreciated.

It will also be seen that the base of the eyelet 7 is flared upwardly or cup-shaped and will permit the crimped lower edge of the hub of the button head to nest therein.

Furthermore, it will be seen that by simply providing the base 7 of the eyelet 6 in this manner with but one thickness of material, it may be quickly and readily stamped out in the proper die.

Referring for the moment to Fig. 6, it will be seen that it is a simple matter to attach the button. As is well known, these buttons are attached in automatic button attaching machines (not shown), the buttons feeding down one hopper and the tacks down another and the tack is then driven up through the cloth 12 and the prong 13 of the tack 14 will pass within the hub of the eyelet, impinge against the dome or cover 9 of the eyelet and be deformed and assume substantially the shape, as shown at 15. Thus, the prong 13 will substantially fill the dome of the eyelet and will widen out, so that it cannot pull out through the hub 8 of the eyelet, in this manner securely fastening the button to the cloth.

It will be seen that the head 1 may move vertically on the eyelet to assume the position shown in Fig. 5 but normally it will remain in the position shown in Fig. 4. It will likewise be able to tilt or cant slightly, as will be also readily appreciated.

By making this dome-shaped eyelet with its integral cover, it will absolutely prevent any chance of the prong piercing the body portion of the button head. Furthermore, the shape of the dome of the eyelet is the same as the shape of the dome portion of the hollow hub of the button head, so that when the button is attached, the dome of the eyelet and the dome of the button head will be snugly held against each other.

In Fig. 7, we have shown a slight modifi-

cation of the eyelet, as the eyelet might be made in this way, although it is quite far more preferable to make the eyelet as shown in the preferred form. However, should the button head be made of say a stainless steel so that a tack could not penetrate the same, the eyelet might be made as shown in this modified form.

It will be seen that the eyelet in this instance has a cupped base 16 exactly similar to the preferred form, has the hollow hub 17 and is flared on its upper edge, as at 18, but does not have the integral dome cover over the hub. In the same manner, when the tack is driven up into the hub, it will deform over the flared portion 18 to thus hold the eyelet in position.

It will be understood, however, that this modified form may be used but at the present time the preferred form is more desirable.

From the foregoing, it will be seen that we have produced a flexible type of button comprising simply a button head on which there may be an ornamental cap and an eyelet that may be quickly and readily fastened to the material and the eyelet, in turn, being simple in construction and preferably with an integral cover over the eyelet, so that a tack prong cannot possibly mutilate the button head.

Finally, it will be seen that the button head may be of relatively thin metal so that the button will be extremely light in weight and, at the same time, there will be no danger of the tack piercing or mutilating the button head or its cap.

Having thus described our invention, what we claim as new and desire to secure by Letters Patent is:

1. A flexible type of button comprising a button head having a hollow hub, a closed top eyelet irremovably fitting within said hub and the base of the eyelet comprising a cup-shaped rim, the outer edge of the rim terminating in a plane normally above the lower edge of the hub of the eyelet, and the upper edge of the hub of the eyelet being outwardly flared and adapted to receive a tack fastener.

2. A flexible button comprising a solid head having a hollow hub, an eyelet fitting within said hollow hub, the head capable of vertical movement on the eyelet but irreversibly held thereto, the button head provided with a metal cap and the base of the eyelet being cup-shaped and terminating above the lower edge of the hub of the button head when the button head is in its normal position.

3. A flexible type of button comprising a solid button head having a hollow hub, an eyelet having parallel sides fitting within said hub and said eyelet having an integral outwardly flared dome-shaped cover, the

lower edge of the hub of the button head crimped under the flared portion of the hub of the eyelet and nesting within the base of the eyelet, and the dome-shaped cover of 5 the eyelet adapted to receive the mutilated end of a tack to thereby hold the button in position.

4. A flexible type of button comprising a solid head and a cap thereon, the button head 10 provided with a dome-shaped hollow hub, an eyelet having a cup-shaped base, a hollow hub and a dome-shaped cover whose diameter is greater than the diameter of the hub of the eyelet, and the hub of the button 15 head crimped beneath the dome of the eyelet whereby the head may move vertically with respect to said eyelet and be irremovably secured thereto.

5. A flexible type of button comprising a 20 button head having a dome-shaped hollow hub, an eyelet fitted within said hub, the eyelet comprising a cup-shaped base, a hollow hub and an outwardly flared integral dome-shaped cover over said hub, the hub of the 25 button head crimped beneath the flared dome of the eyelet and the hub movable vertically with respect to the eyelet, and the dome of the eyelet adapted to receive a mutilated prong of a fastener to thereby secure the button to 30 the article to which it is to be attached.

6. A button of the flexible type comprising a button head and a cap secured thereto, said button head provided with a dome-shaped hub, a correspondingly dome-shaped eyelet 35 having a restricted hub and a cup-shaped base, the lower edge of the hub of the button head crimped beneath the dome of the eyelet to secure said parts to each other and the parts being vertically movable with respect to each 40 other, the cup-shaped base nesting the crimped edges of the hub of the button head, and the dome-shaped eyelet adapted to receive the mutilated end of a tack to thereby hold the button to the article to which it is to 45 be attached.

7. An eyelet comprising a concave base, a hollow hub, an integral convex cover over the hub, and the convex cover being greater in cross sectional diameter than the diameter 50 of the hub of the eyelet and the inner wall of the convex cover adapted to turn the prong of a fastener.

In testimony whereof, we affix our signatures.

55 FRANKLIN R. WHITE.
JOHN J. WOOSTER.
